ATTORNEY.

UNITED STATES PATENT OFFICE.

ROBERT M. KEATING, OF SPRINGFIELD, MASSACHUSETTS.

DESIGN FOR A BICYCLE-FRAME.

SPECIFICATION forming part of Design No. 26,687, dated February 23, 1897.

Application filed October 24, 1895. Serial No. 566,792. Term of patent 14 years.

To all whom it may concern:

Be it known that I, ROBERT M. KEATING, a citizen of the United States of America, residing in Springfield, in the county of Hampden 5 and State of Massachusetts, have invented and produced a new and original Design for Bicycle-Frames, of which the following is a specification, reference being had to the accompanying drawing, illustrating such design.

The illustration is a side elevation of my improved design.

The leading feature of my design consists in the curved lower portion of the central up- 15 right bar of the frame.

It will readily be seen that as the essential feature consists of the central brace curved at its lower end and substantially straight throughout the remainder of its length the particular shape of the remaining portions of 20 the frame are immaterial.

Having therefore described my design, what I claim is—

The design for bicycle-frames herein shown and described.

ROBERT M. KEATING.
